UNITED STATES PATENT OFFICE.

EDWARD C. LOWE, OF NEENAH, WISCONSIN, ASSIGNOR TO KIMLARK RUG COMPANY,
OF NEENAH, WISCONSIN, A CORPORATION OF WISCONSIN.

SHUTTLE.

Application filed September 25, 1924. Serial No. 739,755.

This invention relates to shuttles for looms, but more particularly to tension devices for the same and has for its primary object to provide a simple, economical and 5 efficient device of this character.

Further objects of my invention are to facilitate the threading of the shuttle; to reduce the cost of operation; to allow for the passage of knots; to provide a finer and 10 more rapid adjustment; to eliminate the usual bottom plate; to facilitate repair, particularly of the spring; and in general, to provide a new and improved tension device.

The many other objects and advantages of 15 my invention will be better understood by reference to the following specification when considered in connection with the accompanying drawing, illustrating a selected embodiment thereof, in which:—

20 Fig. 1 is a plan view of a shuttle in which is incorporated a tension device embodying the principles of my invention.

Fig. 2 is a longitudinal section on the line 2—2 of Fig. 1.

25 Fig. 3 is a transverse section on the line 3—3 of Fig. 1, and

Figs. 4 and 5 are detail views.

Referring to the drawings, the present embodiment of my invention is primarily intended for the weaving of rugs where a paper weft or filling is used. Knots of 30 considerable size quite frequently occur in this kind of filling and it is necessary that the tension device permit these to pass through.

35 The usual strap, or cop binder is not illustrated as this has no relation to the filling tension.

The numeral 1 designates the double pointed shuttle body provided with a cavity 40 or chamber 2 having its side walls serrated as at 3 for engagement with the cop 4. In shuttles of this nature particularly intended for heavy work, the yarn or filler 5 is generally stripped from the bobbin and placed 45 in the shuttle chamber without any central support. The natural action of this yarn would be to expand into at least one of the grooves of the saw-tooth formation and by such interlocking relation hold the yarn in 50 place against being driven or jammed forwardly when the shuttle enters the box.

The tension on the yarn is directly provided by oppositely disposed coacting plates 7 and 8, which are shown detached in Figs. 55 4 and 5. The plates 7 and 8 are respectively

known as the upper and lower tension plates. The plate 7 is embedded in the side walls as at 9 and 9' and held in position by a pin as 10. The bottom tension plate 8 is hinged on a pin 11 and presses the filler against the 60 top tension plate 7. A spring 12 acts against the under face of the plate 8 and the pressure is regulated by an adjusting screw 13. A depending lug or rivet 14 is attached to the plate 8 to position the spring 65 12. This spring also permits the bottom plate to yield when a knot passes through the tension device.

A roller 15 is mounted on a stud 16 and secured by a nut 17 seated in a recess 18 in 70 the base wall of the shuttle. The roller is retained on the stud by a washer 19 and screw 20. The roller is preferably flanged at the top 21 to prevent the filler climbing and the top face is cupped as at 22 to facilitate oiling without danger of soiling the 75 filler. The screw fastening 20 enables the roller to be easily removed for cleaning or replacement. The pin 11 is preferably barbed near its point so that it will get a 80 better grip on the wood.

This tension device gives a finer and more rapid adjustment than one using a flat spring. The usual plate on the bottom of the shuttle has been eliminated. Such plates 85 have been the cause of much trouble as the jar causes the plate to become loose. The coil spring does not crystallize or break as quickly as does a flat spring and this spring may be quickly and easily replaced without 90 removing the entire tension device. As soon as the screw 13 is removed, the spring 12 drops out and a new one may be instantly inserted.

The shuttle is threaded by passing the end 95 of the yarn or filler 5 between the tension plates 7 and 8, around the roller as indicated in Fig. 1, and out through the slot 25 provided for the purpose in the side of the shuttle.

The plates 7 and 8 are preferably set at a wide angle to permit filler knots to pass through without being snapped off. The plates permit the filler to flow or run freely 105 and without any slack while the shuttle is in motion, but check it instantly when the shuttle stops. The plate 7 is preferably notched or slotted at 26 to facilitate the threading. The plate 8 is loosely mounted upon its pivot pin and floats to some extent 110

longitudinally or in the same direction as that of the thread, the pivot being substantially provided with a slot for this purpose so that the plate will shift in either direction 5 longitudinally or angularly and give to the tension of the paper weft or thread, especially when passing knots, usually of considerable size in paper weft threads as used for filling, thereby permitting the threads 10 and knots to pass or give to prevent breakage thereof when there is unwinding checking restraint due to contact of the cop or bobbin with the serrated walls of the shuttle. The tension is applied against the upper plate 7 which is preferably rigid. The plates fit closely the roller 15 about 15 which the filling passes as it leaves the shuttle.

It will be obvious from the foregoing description that my shuttle tension device is simple and durable in construction and efficient in operation.

I am aware that numerous changes may be made in the form and arrangement of the parts of my tension device without departing from the spirit of my invention and I reserve the right to make all such as fairly fall within the scope of the following claims.

I claim as my invention:

1. In a shuttle, a body having a chamber, and a tensioning device for the filling as it leaves said chamber, including angularly disposed tensioning plates converging in the direction of advance of the filling, one of said plates being loosely pivoted for movement in the general direction of its length and the converging inner faces of said plates co-acting with said filling on opposite sides.

2. In a shuttle, a body having a chamber, and a tensioning device for the filling as it leaves said chamber, including angularly disposed tensioning plates converging in the direction of advance of the filling, one of said plates being yieldingly pressed towards 45 the other plate and being adapted for limited movement in the same direction as that of the thread.

3. In a shuttle, a body having a chamber, and a tensioning device for the filling as it leaves said chamber, including angularly disposed horizontal tensioning plates converging in the direction of advance of the filling, one of said plates being fixed and the other yieldingly pressed toward said fixed plate and slidable in the direction of its length.

4. In a shuttle, a body having a chamber, and a tensioning device for the filling as it leaves said chamber, including a rotatable 60 and vertically disposed substantially cylindrical member disposed at one side of the chamber and about which the filling passes, and oppositely disposed tensioning plates co-

acting with said member and substantially conforming to the same.

5. In a shuttle, a body having a chamber, and a tensioning device for the filling as it leaves said chamber, including a substantially cylindrical member about which the filling passes, and tensioning plates converging in the direction of travel of the thread and fitting about the periphery of said member and co-acting therewith said plates being mounted independently of the cylindrical member.

6. In a shuttle, a body having a chamber, and a tensioning device for the filling as it leaves said chamber, including a revoluble member about which the filling passes, and a pair of angularly disposed tensioning plates mounted independently of the revoluble member and co-acting with the filling during said passage.

7. In a shuttle, a body having a chamber, and a tensioning device for the filling as it leaves said chamber, including a pair of co-acting flat tensioning plates disposed in angular relation, one of said plates being floating and the other fixed.

8. In a shuttle, a body having a chamber, and a tensioning device for the filling as it leaves said chamber, including a pair of co-acting tensioning plates, one of said plates being hinged for floating action and yieldingly pressed toward the other plate.

9. In a shuttle, a body having a chamber, and a tensioning device for the filling as it leaves said chamber, including a pair of co-acting tensioning plates, one of said plates being fixed and the other floating with limited longitudinal movement, and means for yieldingly pressing said floating plate toward said fixed plate.

10. In a shuttle, a body having a chamber, and a tensioning device for the filling as it leaves said chamber, including a pair of co-acting tensioning plates, one of said plates being fixed and the other plate loosely mounted to permit a limited longitudinal floating movement, and a spring acting against said pivoted plate to yieldingly press the same toward said fixed plate.

11. In a shuttle, body having a chamber, and a tensioning device for the filling as it leaves said chamber, including a roller around which the filling passes and a pair of co-acting tensioning plates fitting the roller, one of said plates being provided with a threading slot to facilitate the insertion of the filling between said plates.

12. In a shuttle, a body having a chamber, and a tensioning device for the filling as it leaves said chamber, including angularly disposed oppositely inclined top and bottom tension plates arranged in a horizontal direction extending transversely of the chamber.

and converging in the direction of the advance of the filling, the top plate being rigid and fixed and the bottom plate yieldingly pressed toward the top plate and movable in the direction of its length.

13. In a shuttle, a body having a chamber, and a tensioning device for the filling as it leaves said chamber, including a roller mounted near one side of the chamber and around which the filling is trained, said roller having an outwardly extending inclined flange at the top, and fastening means engaged within the same, and transversely disposed tensioning plates in the chamber cut to conform to the periphery of the roller.

14. In a shuttle, a body having a chamber, and a tensioning device for the filling as it

leaves said chamber, including a plurality of co-acting tensioning plates, at least one 20 of said plates being fixed, and at least one of said plates being loosely pivoted to permit floating movement thereof bodily in the same direction as that of the thread.

15. In a shuttle, a body having a chamber, 25 and a tensioning device for the filling as it leaves said chamber, including a pair of co-acting tensioning plates, one of said plates being fixed, a pivot pin on which the other plate is loosely pivoted for movement in substantially the same direction as that of the thread, and adjustable spring means for holding the plates yieldingly pressed together.

EDWARD C. LOWE.
